UNITED STATES PATENT OFFICE.

RUTH E. NEWTON, OF ELIZABETH, NEW JERSEY, ASSIGNOR TO CAMPBELL ART COMPANY, OF ELIZABETH, NEW JERSEY, A CORPORATION OF NEW JERSEY.

PAPER DOLL.

Application filed August 3, 1921. Serial No. 489,429.

To all whom it may concern:

Be it known that I, RUTH E. NEWTON, a citizen of the United States, residing in Elizabeth, in the county of Union and State 5 of New Jersey, have invented certain new useful Improvements in Paper Dolls, of which the following is a specification.

This invention relates to cut-out paper dolls, and is illustrated in the form of a 10 greeting card, although it is also useful for advertising cards and other purposes.

Cut-out dolls, especially those forming parts of greeting cards and other cards, have usually been made by printing the dress 15 portions as well as the lineaments of the doll, so that the attractiveness consisted mainly in the design of the doll and dress.

The principal object of the invention is to devise an inexpensive, simply made card, 20 doll or figure of striking appearance, capable of a variety of uses, and to enhance the appearance of dolls of this nature, this being effected by providing the cut-out doll with a paper dress of improved construction and 25 application.

The invention provides a novel method of preparing miniature figures and applying thereto apparently real skirts and other articles of apparel, such as capes, scarfs, collars, hats and parasols. These figures may 30 be specially prepared for the purpose, and may be reproductions of models or of designs. These reproductions may be made on either paper or card-board, and in some 35 cases portions thereof may be produced in clay, plaster, bisque, metal or other suitable material.

Heretofore the operation of attaching to card or paper dolls certain materials to represent wearing apparel, has been expensive and laborious. An object of the present invention is to facilitate, simplify and reduce the cost of making and applying such apparel, and make it seem real. The novel 45 method involves making the miniature figure in parts. If the article to be applied is in the nature of a skirt, one part of the figure may consist of the head and body, while the other part may consist of the 50 lower limbs and a portion of the body. There is an overlapping arrangement of these parts. The skirt or other article of adornment is cut out or stamped in quanti-

ties, by means of dies, from the desired materials, the dies giving the article the required shape. The flat skirt is then applied to one of the parts of the figure. Then the figure is completed by attaching the second part to the first part. By proceeding in this manner, it will be seen that the flat skirt apparently encircles the figure, being placed over one of these body parts and under the other one, so as to give the appearance of actual wearing apparel. This effect is enhanced by having the upper part of the figure overlap the lower part, or extend down partly over the skirt, said upper part ending at the waist line, so that the waist appears to extend out from the skirt. The same method can also be adopted for applying a collar, in 65 which case the head part will be made separately from the upper body, and then the collar may be stamped out and applied to the body above the shoulders, whereupon the head and neck portion may be applied to 70 said upper body portion, so that the collar will encircle the neck, part of the collar passing behind the head of the figure. A similar method may be employed for capes and scarfs, etc. It is believed to be novel to 75 encircle the card or figure with wearing apparel.

Other features and advantages will hereinafter appear.

In the accompanying drawings, 85 Figure 1 is an elevation of one form of doll embodying the present improvements.

Figure 2 is an edge elevation of the same.

Figure 3 is a rear elevation of the doll.

Figure 4 shows the upper body portion of 90 the doll.

Figure 5 shows the lower body portion with the skirt attached thereto.

Figure 6 shows the skirt and underskirt.

Figure 7 shows the lower body portion. 95

The dress consists preferably of a skirt A, which is preferably in the form of a ballet dancer's skirt. There may also be an underskirt B, both skirts made of paper, the outer skirt being colored and the under- 100 skirt preferably white. In order to produce the dolls inexpensively, and at the same time make them attractive, the skirts A and B may be made of creped tissue paper, thus giving them a similarity to 105 cloth skirts. In place of hanging the skirt

in the usual form of a bell upon the doll, the skirt is preferably made in the form of a disk, which is hung upon the doll at or above the waist-line C. The skirt is trans-
5 pierced by the doll. The piercing line G is located at the top of the skirt, i. e., at the waist of the doll. The lower edge or portion of the skirt flares downwardly in front of the lower portion D of the doll, and upwardly in rear of the upper portion E of the doll, to give a ballet skirt effect, with inexpensive paper.

In order to construct the doll, it is made of the two parts D and E, divided at about 15 the waist-line C. The lower part D terminates at its upper end above the waist-line in a tab or tongue F, which is relatively narrow, and upon this tab are slipped the skirts A and B, which have central perforations or slits G large enough to enable them 20 to be placed upon the tab. The slit G is only long enough to enable the skirt to be slipped upon the tab and down against the broader main portion of the doll at H.

25 The skirt having been attached, the upper portion E of the doll body is pasted upon the tab at J, this entire upper portion E being in front of the upwardly flaring portion of the skirts A and B.

30 The doll may stand upon a base portion K of the card, and the latter may have pasted to the back thereof a foot L, which may be opened out to enable the doll to be stood upon a mantel or table.

35 The invention is not limited to paper or other cut-out dolls, so long as each doll is made of separate parts, preferably the upper of which overlaps the front of the lower; the skirt, cape, collar or other article 40 being applied to one of said parts before attaching the two parts together.

45 Variations may be resorted to within the scope of the invention, and portions of the improvements may be used without others.

Having thus described my invention, I claim:

1. A cut-out paper doll provided with a flat disk-like skirt of the ballet type trans-
50 pierced by the doll, the piercing line being at the top of the skirt, and the bottom of the skirt flaring both in front of the lower part of the doll and in rear of the upper part of the doll.

55 2. A cut-out paper doll provided with a flat disk-like skirt of the ballet type trans-
pierced by the doll, the piercing line being at the top of the skirt, and the bottom of the skirt flaring both in front of the lower 60 part of the doll and in rear of the upper part of the doll, said doll formed of upper and lower parts attached at about the waist-line, the skirt being placed in front of the lower part and in rear of the upper 65 part.

3. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed. 70

4. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed, the upper part of the doll being also attached to said tab. 75

5. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed, the skirt having a perforation or slit through 80 which the tab extends. 90

6. A cut-out paper doll provided with a flat-disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed, the upper part of the doll being also attached to said tab, the skirt having a perforation or slit through which the tab extends. 100

7. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed, the upper part of the body being attached to said tab. 110

8. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed, the upper part of the body being attached to said tab, above the point where the skirt is attached to the tab. 115

9. As a new article of manufacture, a crepe paper disk to form a ballet skirt for a cut-out paper doll, said disk having a central slit or perforation for attachment of the skirt upon the doll, said slit being at the 120 130

top of the skirt, and the bottom or edge of the skirt flaring upwardly and downwardly from said slit.

10. A cut-out paper doll comprising an upper portion extending down to the waist-line and a lower portion behind said upper portion and having a tab whereby it is attached to the upper portion above the waist-line.

10 11. A cut-out paper doll comprising an upper portion extending down to the waist-line and a lower portion behind said upper portion and having a tab whereby it is attached to the upper portion above the waist-line, and an attached ballet skirt intervening between said portions, said skirt being transpierced by the doll, the piercing line being at the top of the skirt, and the bottom of the skirt flaring both in front of the lower part of the doll and in rear of the upper part of the doll.

12. A cut-out paper doll comprising an upper portion extending down to the waist-line and a lower portion behind said upper portion and having a tab whereby it is attached to the upper portion above the waist-line, and a skirt caught upon said tab, said upper portion being attached to said tab in front of the skirt.

30 13. A cut-out paper doll provided with a flat disk-like skirt hung upon the doll at the waist-line, said doll formed of upper and lower parts attached at about the waist-line, the skirt being placed in front of the lower part and in rear of the upper part, the lower part terminating at its upper end in a tab upon which the skirt is placed,

and a second paper disk placed on said tab under the first skirt to form an under-skirt.

14. A paper doll having upper and lower portions which overlap at about the waist-line, said doll encircled by a flat skirt transpierced by the doll and passing between said overlapping portions and flaring both down in front of the lower portion and up in rear of the upper portion.

15. The method of making a dressed miniature figure, comprising forming the figure in two overlapping parts, with a tab, tongue or projection upon one of said parts, applying an article of apparel upon said tongue or projection, and attaching the other of said parts to said projection.

16. The method of producing a dressed paper or card doll, comprising making the body in two overlapping portions, with a tab or projection upon one of said portions, slitting an article of wearing apparel, inserting said tab or projection through the slit, and then attaching the other of said portions to said tab or projection.

17. The method of producing a dressed paper or card doll, comprising making the body in two overlapping portions, with a tab or projection upon one of said portions, forming a flat paper skirt with a slit, inserting the tab or projection through the slit in the skirt, and attaching the other part of said body to said tab or projection.
